UNITED STATES PATENT OFFICE.

JOHN H. UNDERWOOD, OF MARLBORO, MASSACHUSETTS, ASSIGNOR OF ONE-HALF TO THE S. H. HOWE SHOE COMPANY, OF MARLBORO, MASSACHUSETTS, AND BOSTON, MASSACHUSETTS, A CORPORATION OF MASSACHUSETTS.

MACHINE FOR SKIVING HEEL-RANDS.

SPECIFICATION forming part of Letters Patent No. 715,907, dated December 16, 1902.

Application filed January 31, 1902. Serial No. 91,982. (No model.)

To all whom it may concern:

Be it known that I, JOHN H. UNDERWOOD, a citizen of the United States, residing in Marlboro, in the county of Middlesex and 5 State of Massachusetts, have invented new and useful Improvements in Machines for Skiving Heel-Rands, of which the following is a specification.

This is a machine for skiving heel-rands, 10 the rand being presented to the machine in its curved or horseshoe shape and skived or beveled on its inner edge. In my improvement a vertically-set ring-shaped rotary knife or cutter is mounted on the stationary part of 15 the frame, a pile of rands is fed up to the cutter, the lowest rand is skived, held down during the skiving process, and dropped, another rand presented to the cutter, and so on, the pile of rands being held in a stack and re- 20 plenished at the top. While the rand is being operated on by the cutter, the bed or table on which it lies is swung downward at its forward edge and back into a horizontal position in order to act on the middle or closed portion of the rand and then lower the rand out 25 of contact with the cutter.

The nature of the invention is fully described in detail below and illustrated in the accompanying drawings, in which—

30 Figure 1 is a plan view of my improved machine with the stack removed. Fig. 2 is a vertical section taken on line X, Fig. 1, with the stack in position. Fig. 3 is an enlarged view, in vertical section, taken in front of the 35 revolving knife. Fig. 4 is a view of the rand or product after it has been operated on by the machine.

Similar numerals of reference indicate corresponding parts.

40 A suitable frame 1 has mounted on it a table 2, which is normally in a horizontal position. This table is provided with slideways 3, in which a bed 4 is adapted to slide and reciprocate horizontally. This bed is provided 45 with a depression 5, on which stands and is secured in any suitable manner by means of its flanges 6 a stack 7 of suitable shape to receive and fit around a pile of rands 8 to be skived, said rands being held down by a

weight 9. This stack of rands stands between the forward edge of the bed and the shoulder 10, formed by the depression or recess 5. The rear ends of the ways 3, which form a part of the table 2, are connected by a plate 11, which is screwed at 12 to the upper surface of the table, the lower surface of said plate being higher than the upper surface of the recessed or depressed portion 5 by the thickness of one rand.

The table 2 is not rigid with the frame 1, 60 but is supported thereby near its front and rear edges in the following manner: Near the front edge it is provided on its under side with downwardly-extending ears 13, extending transversely with the table on opposite sides 65 of the horizontal shaft 14, on which are mounted eccentrics 15, Fig. 2, which are preferably four in number, as indicated by dotted lines in Fig. 1. This shaft is mounted in a suitable box 16, supported by the frame, and has 70 loose on it a disk-wheel 17, which is, however, rigid on the frame. Fast on the shaft is an arm 18, into suitable recesses upon the outer face of which a spring-pin 19 is held normally by a spring 20. By the above-described means 75 the shaft is pivotally mounted near its forward end on the frame, resting directly on the eccentrics 15, and may be raised or lowered by rotating the shaft by means of the arm 18 and locked in such position by the spring-pin 80 19. By this mechanism the machine is enabled to cut deeper or shallower skives or bevels in the rand, as desired, in the manner below described.

The rear portion of the table 2 is supported 85 by the cam-wheel 21, on whose periphery rests the roll 22, secured to the lower end of the stud 23, which extends up through the plate 11, Fig. 2, and is secured thereto by a suitable nut 24 on the upper side of the plate and 90 by its shoulders 25 on the under side thereof, said stud being threaded at its upper end to accommodate the bolt. Secured to the face of the cam 21 is a disk 26, provided with the slot 27, in which slides the wrist-pin 28, connected by the eccentric arm 29 with the pivot 30, sustained by means of suitable ears 31, secured to the under side of the table 2. Thus

the rear edge of the table is adapted to swing down and up as the cam 21 is rotated, while the front end is set pivotally at the desired elevation on the eccentrics 15. Proper adjustment is made by means of the slot 27. The cam 21 is rigid on a suitable horizontal shaft, (indicated by dotted lines 32 in Fig. 2,) and rigid on the same shaft is a gear-wheel (indicated by dotted lines 33 in Fig. 2) which is engaged by the gear-wheel 34, (shown in dotted lines in Fig. 2 and in full lines in Fig. 1,) which is rigid with or on the same sleeve with the gear-wheel 35 on the fast pulley 36, communicating with the power.

15 The knife or cutter consists of the vertically-disposed ring 37, of which 38 is the cutting edge, said ring extending down into the space between the plate 11 and table 2, as shown in Figs. 1 and 2, and the cutting edge 20 facing the stack of rands. This rotary cutter is rigidly secured to the ring or body portion 39 of a gear-wheel provided on its face with gear 40, said gear-wheel being secured by segmental keys 41 and bolts 42 to a ring 25 43, Figs. 2 and 3, said keys lying in coincident grooves in the gear-wheel and ring. The ring is not, however, a complete ring, as it is cut away at the bottom, as shown in Fig. 3, in order to accommodate the rand as it 30 feeds up to the knife, and the ring is provided with braces 44, Fig. 3, to prevent expansion and is integral with the bracket 45, Fig. 1, which is bolted to the bracket 46, rigidly connected with the sleeve 47 on the stud 35 48 and the frame. This sleeve is provided with suitable clamps 49 and is provided with the pinion 51, which is engaged by the gear-wheel 35. On the other end of this stud is the bevel-gear 50, which engages with the 40 gear 40, above described.

Mounted transversely on and next the front edge of the table 2 is a raised strip 52, bolted to the table at 53. This strip is on a level with the plate 11 and is recessed at 54 45 on its under side, Fig. 2, to accommodate a beveled foot 55, secured to the lower end of a pin 56, which extends through the strip and is held down by a spring 57, so that the foot projects a little below the under surface 50 of the strip. The inner edges of the plate 11 and strip 52 are adapted to receive the two transversely-sliding plates 58, Fig. 3, each of which is beveled on its inner edge to fit the cutter or knife 37, and each has mounted on 55 it a post 59, Figs. 1, 2, and 3. From these posts horizontal rods 60 extend toward each other, said rods being provided at their inner ends with right and left threads, respectively, and being connected by a similarly-threaded nut 61. By means of this nut the plates may be adjusted closely to the cutter, whatever may be the relative height of the plate 11. I prefer to accommodate the sliding plates 58 by a dovetail 64 on the inner 60 edge of the plate 11 and by a bevel 65 on the inner edge of the strip 52, as shown in Fig. 2. The inner ends of the right and left screws

extend through ears 68, Figs. 2 and 3, extending up from the plate 69, and are set by suitable nuts 70.

I prefer to employ also a grinding-wheel 62 for the cutter, said wheel being operated by suitable mechanism 63; but I do not claim any novelty in the wheel or in its actuating mechanism.

The practical operation of the machine is as follows: The cam 21 having been set in the proper position with relation to the wrist-pin 28, and hence to the sliding bed 4, and the bed having been set by means of the mechanism 18, 19, and 20 at the proper height for the rands to be operated upon, power is applied to the machine by means of the pulley 36. The parts being in the position indicated in Figs. 1 and 2—that is to say, the cam-roll 22 being in engagement with the cam 21 at the point illustrated and a pile of rands 8 being in the stack and said stack being next the strip 52—the cam is rotated by means of the intermediate mechanism, which includes the gear-wheels 35, 34, and 33, such rotation drawing the bed 4 to and under the knife 37 38, which is rotated by means of the gear 39 40, the bevel-gear 50, and mechanism intermediate with said gear and the gear-wheel 35. During the first part of the rotation of the cam the lowest rand 8 is carried forward by the bed and, pushing up the beveled foot 55, raises the pin 56 and, advancing, comes in contact with the edge 38 of the rotating knife. As the rand continues to advance the knife begins to cut simultaneously the outer ends 66 of the skives or bevels (indicated at Fig. 4) in the rand. As the rand advances until, say, one-half of it has passed under the knife the bed 4 slides on a horizontal plane without dipping; but when the point 67 in the cam has been brought under the cam-roll 22 the forward end of the table 2 (which supports the bed 4) begins to dip or drop, and while it is 110 swinging down the advance of the bed causes the central portion 67, Fig. 4, of the rand to come in contact with the cutter, and the skive or bevel is completed in the manner indicated in said Fig. 4. As the cam continues to rotate the bed begins its return and the rear edge of the completed rand is brought against the vertical edge of the foot 55, with the result that the pile of rands above it continues to advance toward the front of the machine, 120 leaving the lowest rand, which has been skived, to drop through the machine into a suitable receptacle. During the above process of skiving the rand there is a tendency for the rand to rise, and this tendency is overcome by the pressure of the sliding plates 58, 125 under which the rand passes (see Fig. 3) as it is carried forward by the bed 4. The raised plate 11 allows room for the advancing end of the rand to pass under it during the skiving process. The operation having been completed and the parts returned to their original position, the roll 22 is again at the highest point on the cam 21, and the skiving process

is applied to the next rand, which takes the place of the first rand and is held firmly down by the weight 9.

Having thus fully described my invention, 5 what I claim, and desire to secure by Letters Patent, is—

1. In a machine for skiving heel-rands, a circular knife adapted to rotate in a vertical plane and set to face the open end of the approaching rand; a horizontally-sliding bed; means for supporting a rand on said bed; mechanism for moving said bed toward and from the face of the circular rotating knife whereby the rand is brought in contact with 15 said knife and approaches it with its open end forward; and mechanism for causing the forward end of the sliding bed to swing down or dip while the knife is operating on the rand.

2. In a machine for skiving heel-rands, a circular knife adapted to rotate in a vertical plane and set to face the open end of the approaching rand; a horizontally-sliding bed; means for supporting a rand on said bed; mechanism for moving said bed toward and 25 from the face of the circular rotating knife whereby the rand is brought in contact with said knife and approaches it with its open end forward; mechanism for causing the forward end of the sliding bed to swing down or 30 dip while the knife is operating on the rand; and mechanism for holding down the forward end of the rand while it is being skived.

3. In a machine for skiving heel-rands, a circular knife adapted to rotate in a vertical plane and set to face the open end of the approaching rand; a horizontally-sliding bed; means for supporting a rand on said bed; mechanism for moving said bed toward and from the face of the circular rotating knife 40 whereby the rand is brought in contact with said knife and approaches it with its open end forward; mechanism for causing the forward end of the sliding bed to swing down or dip while the knife is operating on the rand; and mechanism for preventing the return of 45 the rand and for pushing it off the bed, after the skiving process, and while the bed is returning to its original position.

4. In a machine of the character described, 50 the frame; the table provided with suitable ways; the recessed bed 4, 5 adapted in its recessed portion to sustain a stack of heel-rands; the circular knife 37, 38 mounted vertically on the frame and with its cutting edge facing 55 the bed; mechanism for raising and lowering the front edge of the table; the cam 21 mounted in the frame and provided with the slotted disk 26; mechanism intermediate of the cam and the bed whereby horizontal reciprocating 60 movement toward and from the knife is applied to the bed; mechanism intermediate of the cam and the rear portion of the table whereby the table and bed are dipped or swung down and returned to their original

position during the rotation of the cam; mechanism for imparting rotation to the cam; and mechanism for imparting rotation to the knife, substantially as described. 65

5. In a machine of the character described, the frame; the table provided with suitable 70 ways; the bed adapted to reciprocate horizontally on the table; the vertically-set circular rotary knife facing the reciprocating bed and mounted on the frame; the plate 11 mounted on the table beyond the knife; the strip 52 75 mounted on the table between the knife and bed and parallel with the advancing edge of the latter; the pin 56 provided at its lower end with the beveled foot 55 and supported on said strip; mechanism for dipping and returning to its original position the rear end of the table in which the bed slides; and mechanism for rotating the knife, substantially as set forth. 80

6. In a machine of the character described, 85 the frame; the table provided with suitable ways; the bed adapted to reciprocate horizontally on the table; the vertically-set circular rotary knife facing the reciprocating bed and mounted on the frame; the plate 11 90 mounted on the table beyond the knife; the strip 52 mounted on the table between the knife and bed and parallel with the advancing edge of the latter; the transversely-sliding plates 58 supported at their opposite edges 95 by said plate 11 and the strip, and extending under the knife from opposite sides over the opposite edges or legs of the rand being skived; means for moving said sliding plates toward and from each other; mechanism for 100 dropping and returning to its original position the rear end of the table in which the bed slides; and mechanism for rotating the knife, substantially as described. 105

7. In a machine of the character described, 110 in combination with a horizontal sliding table carrying the rands; of the vertical circular knife 37, 38 having a circular cutting edge facing the advancing bed; the ring gear-wheel 40, 43; the body portion of said wheel 115 and that of the knife being provided with coincident annular grooves; and the body portion 43 of the gear-wheel being cut off at its lower end to accommodate the rand and the mechanism for holding down the same; the 120 segmental keys 41 lying in said coincident grooves; bolts extending through the ring 43 and setting against said segmental keys; and mechanism for imparting rotation to the knife, substantially as set forth. 120

In testimony whereof I have signed my name to this specification in the presence of two subscribing witnesses.

JOHN H. UNDERWOOD.
